DESIGN FOR A LIGHTPROOF MESSAGE DISPATCH BOX

Thomas J. Gorman, Jr., Newark, N. J.

Application January 14, 1942, Serial No. 105,196

Term of patent 3½ years

To all whom it may concern:

Be it known that I, Thomas J. Gorman, Jr., a citizen of the United States, residing at 70 Oriental Street, in the city and county of Newark, and State of New Jersey, have invented a new, original, and ornamental Design for a Lightproof Message Dispatch Box, of which the following is a specification, reference being had to the accompanying drawing, forming part thereof.

Fig. 1 is a perspective view of a lightproof message dispatch box showing my new design,

with the box shown in open position and the bellows in expanded position.

Fig. 2 is a perspective view of the lightproof message dispatch box shown in Fig. 1, shown in closed position.

Fig. 3 is a side elevational view of the lightproof message dispatch box shown in Fig. 1.

I claim:

The ornamental design for a lightproof message dispatch box, as shown.

THOMAS J. GORMAN, JR.
